UNITED STATES PATENT OFFICE

2,632,445

DOSING HYPODERMIC SYRINGE

John L. Kas, Sr., Boston, Mass.

Application October 20, 1951, Serial No. 252,334

5 Claims. (Cl. 128—218)

1

This invention relates to a hypodermic syringe having a piston movable in a hollow cylinder to eject the contents of the cylinder through the needle, and a mechanism operable to move the piston step-by-step for the discharge of accurately measured amounts of the liquid in the cylinder through the needle. This is done by means of a ratchet device manually operable to advance the piston. The parts of the device are easily assembled or disassembled to facilitate thorough cleaning.

For a more complete understanding of the invention reference may be had to the following description thereof and to the drawing, of which:

Figure 1 is an elevational view of a syringe embodying the invention, showing how it is held;

Figure 2 is an elevational view of the same from a different angle and on a larger scale;

Figure 3 is an elevational view, partly broken away to show the parts in section;

Figure 4 is a section on the line 4—4 of Figure 3; and

Figure 5 is an enlarged fragmentary sectional view of some of the parts shown in Figure 3, but in different relative positions.

The syringe illustrated on the drawing includes a cylindrical barrel 10 having a fitting 12 at one end by which a hollow hypodermic needle 14 can be attached and detached. The barrel 10 may be made of metal with a glass lining 15 a portion of which shows through an elongated opening 16 through which the amount of liquid in the barrel can be seen. At the other end of the barrel is a removable head 20 which may be screw threaded directly on the barrel, or, as shown in Figure 3, may be screw threaded into a collar 22 which is threaded on the end portion of the barrel. The head 20 has a central tubular extension 24 through which projects a piston rod 26 one end of which is attached to a piston 28 slidably fitted within the barrel 10. The piston rod 26 is provided with ratchet teeth 30 which may conveniently be in the form of circumferential grooves extending around the rod so that the rod can operate in any angular position in which it happens to be. A tubular reciprocal member 32 is slidably mounted on the rod 26, this member having a transverse plate 34 from which a short tubular portion 36 extends toward the barrel to telescope with the tubular projection 24 from the head 20. A spring 38 is compressed between the head 20 and the plate 34 so as to press the tubular member 32 constantly away from the barrel 10. The movement of tubular member 32 away from the barrel is limited by

any suitable means such as a bolt 40 screwed into the head 20, the bolt having a head 42 which engages the outer face of the plate 34. The bolt 40 passes through a hole or notch 44 in the blade 34. 5 To cooperate with the ratchet teeth 30 a pawl 50 is pivotally mounted as at 52 in a slot 54 in the plate 34. This pawl is pressed yieldingly against the rod 26 by a suitable spring 56. The slot 54 extends into the bore of the member 32 so as to provide access for the pawl 50 to the rod 26 and the teeth 30 thereon. A finger piece 58 is provided at the end of the pawl 50 to facilitate manual movement of the pawl to disengage it from the teeth 30. A detent 60 is similarly mounted in a slot 62 in the head 20, this slot extending in to the bore of the tubular extension 24 so as to provide access for the detent 60 to the rod 26. A spring 64 is mounted in the slot 62 to press the detent 60 yieldingly against the rod 26. The tubular extension 24 may be provided with an exterior shoulder 66 thereon to be engaged by the end of the tubular portion 36 on the member 32 to limit its movement when it is pushed toward the barrel. The length of the bolt 40 is selected so that the range of movement of the member 32 is slightly more than the distance from one tooth 30 to the next. Mounted on the member 32 is a thumb piece 68 which is adapted to be pressed by the thumb in the manner illustrated in Figure 1. A reinforcing member 70 is secured to the plate 34 and the thumb piece 68 to stiffen the latter. On the head 20 suitable finger pieces 72 and 74 are provided to be gripped by the first two fingers of the hand 35 when the thumb presses on the thumb piece 68. In the embodiment of the invention illustrated on the drawing the finger pieces 72 and 74 are in the form of circular rings but these members may be otherwise shaped if desired.

40 The detent 60 is provided with a finger piece 76 at its outer end, this being arranged adjacent to the finger piece 58 on the barrel 50 so that both the bolt and detent can be simultaneously swung out against their springs to permit retraction of the rod 26. At the outer end of the rod is a finger piece 80 to facilitate the retraction of the rod when the pawl and the detent are pushed out of engagement with the teeth 30. When the rod has been retracted, the thumb piece 68 can be pressed repeatedly to cause the piston 28 to move forward by equal steps. If the barrel contains liquid, this will be ejected in successive doses.

When the thumb piece is pressed the pawl 55 50 which is in engagement with one of the teeth

30 causes the rod 26 and piston 28 to advance until the end of the tubular element 36 hits the shoulder 66. This advance of the rod 26 causes the detent 60 to catch on the next successive tooth 30 so as to hold the rod against retraction when the thumb piece is released to let the spring 38 move the member 32 back to its original position ready for another actuation.

I claim:

1. A hypodermic syringe comprising a barrel, 10 a piston reciprocable in said barrel, a piston rod extending from said piston out through an end of said barrel, circumferential grooves in said rod forming a series of ratchet teeth, a tubular member slideable on said rod, means 15 limiting the range of movement of said member relative to said barrel, a spring-pressed pawl carried by said member and yieldingly held against said rod, a spring pressing said member in a direction away from said piston, and a 20 spring-pressed detent carried by said barrel and pressing against said rod.

2. A hypodermic syringe comprising a barrel, a piston reciprocable in said barrel, a hollow needle projecting from one end of the barrel, 25 a detachable head on the other end of the barrel, a piston rod extending from said piston out through said head, finger pieces mounted on said head, ratchet teeth on said rod, a tubular member slideable on said rod, means limiting the 30 range of movement of said member relative to

said barrel, a compression spring between said head and member pressing the member away from the head, a spring-pressed pawl carried by said member and pressed against said rod, 5 and a spring-pressed detent mounted on said head and pressed against said rod.

3. A syringe as in claim 1, said tubular member having a thumb-piece to facilitate manual operation thereof.

4. A syringe as in claim 1, said head having a central tubular projection in telescoping relation with said tubular member.

5. A syringe as in claim 1, said pawl and detent having projections located in juxtaposition to facilitate simultaneous movement of said pawl and detent out of engagement with said ratchet teeth to permit retraction of the piston and rod.

JOHN L. KAS, SR.
